United States Patent Office

Des. 191,160
Patented Aug. 22, 1961

191,160

WATER CLOSET

Frederick David Chapman, Chicago, Ill., assignor to The Murray Corporation of America, Pittsburgh, Pa., a corporation of Delaware

Filed Jan. 15, 1960, Ser. No. 59,053

Term of patent 14 years

(Cl. D4—5)

FIG. 1

Des. 191,160

PAGE 2

FIG. 3

FIG. 2

FIG. 4

FIG. 5

FIGURE 1 is a front perspective view taken from the right side of the water closet embodying my design;

FIGURE 2 is a front elevational view thereof;

FIGURE 3 is a rear elevational view thereof;

FIGURE 4 is a top plan view thereof; and

FIGURE 5 is an elevational view taken from the left side of FIGURE 1.

The dominant features of my design reside in the portions shown in full lines.

I claim:

The ornamental design for a water closet, as shown and described.
